(57) **CLAIM**

We claim the ornamental design for the bed bug guard, as shown and described.

DESCRIPTION

FIG. 1 is a perspective view of the first embodiment of the bed bug guard;

FIG. 2 is a front view of the first embodiment of the bed bug guard;

FIG. 3 is a top view of the first embodiment of the bed bug guard;

FIG. 4 is a side view of the first embodiment of the bed bug guard;

FIG. 5 is a perspective view of a partial cross section of the first embodiment of the bed bug guard;

FIG. 6 is a front view of the partial cross section of the first embodiment of the bed bug guard;

FIG. 7 is a top view of the partial cross section of the first embodiment of the bed bug guard; and,

FIG. 8 is a side view of the partial cross section of the first embodiment of the bed bug guard.

The design is the shape and visual features of the bed bug guard.
